BRASSIÈRE

Henry M. Plehn, New York, N. Y.

Application June 3, 1947, Serial No. 752,153

3 Claims. (Cl. 2—42)

1
This invention relates to a brassière.

One of the prime purposes of the brassière is to support the female breast in a normal, comfortable and unrestricted position. The usual type brassière is built in various cup sizes to accommodate differences in breast size. These rigid type brassières are fundamentally wrong in that they do not perform properly for the women whose breast size falls between cup sizes such as for example, a B-minus or B-plus. Nor does it consider the change in breast size that occurs in the female during the monthly cycle. Even in the proper breast size, most brassières envelop or bind the breast in such a fashion that normal circulation and freedom of movement is constricted. Many cases of breast cancer have been attributed to such breast constriction as caused by improperly fitted brassières.

It is therefore the main object of this invention to provide a brassière that will permit positive control of the breasts without any binding or constriction no matter what the deviation of the breast size may be away from the normal.

Another object of this invention is to provide a brassière that allows the breasts to expand and contract during breathing movements while keeping the base or body of the brassière anchored.

Still another object of this invention is to provide a brassière that will follow the changing contour of the breasts during the monthly cycle and supply the same positive control without binding or constricting the breasts.

Other objects and advantages will appear from the following description considered in connection with the accompanying drawings, in which:

Fig. 1 is a front elevational view of the brassière.

Fig. 2 is a rear elevational view of the brassière shown in Fig. 1.

Referring now to the structure of the brassière shown in the drawings, said brassière comprises a pair of breast-receiving sections 1 and 2, having a plurality of segments 3 which are joined together by stitching 4 which make criss-cross lines 5 and 6 across the face of the section whereby the cup-shaped contour is attained. A connecting strip 7 composed of elastic material is stitched to substantially three-quarters of the periphery of the cup-shaped sections 1 and 2 excepting the top portion. In substantially the center of the elastic material 7, between said cup-shaped sections 1 and 2 is stitched a stiffening member 8 which is of any suitable non-elastic material. To the outer edges of said elastic material 7 are stitched supporting bands

2
9 and 10 adapted to encircle the body of the wearer and made of any suitable non-elastic material having reinforced stitched borders 11 along the outer edges. At one end 12 of said band 9 is stitched a plurality of hooks 13 while to the end 14 of said band 10 is stitched an elastic strap 15 which has attached to its free end 16, paired hook-eyes 17 and 18 which are spaced at different distances from the edge 16 of said elastic strap 15.

Attached to the upper non-elastic edges 19 and 20 of said cup-shaped sections 1 and 2 respectively, are ends 21 and 22 of paired shoulder straps 23 and 24 while the other ends 25 and 26 of said shoulder straps 23 and 24 are stitched to the upper outer edges 27 and 28. Said shoulder straps 23 and 24 may be adjusted by means of buckles 29 and 30 respectively.

An elastic strip 31 is sewn through substantially the center of the elastic arcuate portions 32 and 33 of the elastic strip 7 which follows the contours of the cup sections 1 and 2 respectively. The floating ends 34 and 35 of said body encircling bands 9 and 10 are interconnected partially by said elastic material 7 and an elastic strap 36 sewn to the inside of said elastic materials 7 and said floating ends 34 and 35 of said bands 9 and 10.

In the wearing of the garment described above, said breast cup sections 1 and 2 are held in position on the breasts by the body encircling bands 9 and 10, yet said cup sections 1 and 2 float free on the interconnecting strip 7 of elastic material so that said cup sections 1 and 2 will follow the changing contour of the breast during breathing and during any other natural breast changes as described above. During the floating movements of the breasts and their supporting cup sections 1 and 2, said central stiffening member 8 supplies the necessary separation to maintain said breasts in the normal separated position.

The normal breathing movements of the chest are further facilitated by the elastic band 36 which interconnects the floating ends 34 and 35 of said non-elastic cloth of the encircling body bands 9 and 10 whereby the entire brassière covering the front of the chest expands and contracts under pressure of the breathing movements of the wearer.

As will be seen from the above description, the invention discloses a brassière which allows for expansion and contraction of the chest cavity yet supplies positive control of the contour of the female breasts.

In addition, said brassière provides "floating" cup-shaped sections which hug the changing contours of the female breasts and provide comfortable control of breasts that may not fit into the normal cup sizes of the standard brassière.

While, in disclosing the principles of my invention and its preferred embodiment, I have described various detailed structure and relationship, it will be understood that such embodiment and details are given by way of example only 10 and not as limiting the scope of my invention.

I claim:

1. A brassière comprising a pair of cup-shaped receiving sections, a pair of supporting bands adapted to encircle the body of the wearer, said supporting bands having inner ends and outer ends, the inner ends being proximate and shaped to conform to the side and bottom contour of the bust receiving sections, and terminating in floating portions below said bust receiving sections, 20 said floating portions being separated from one another by a small gap, an elastic member having a portion filling said gap, connecting said floating ends, and a portion, arcuate in shape, connecting the bust receiving sections to the supporting 25 bands and connecting the bust receiving sections.

4
to one another, and another elastic member arcuate in shape secured to the arcuate portions of said first mentioned elastic member.

5 2. A brassière as claimed in claim 1, including another elastic member secured to the portion of the first elastic member that fills the gap between the floating ends and connects said floating ends.

3. A brassière as claimed in claim 1, including a separation member secured to the first mentioned elastic member between said cup shaped receiving sections.

HENRY M. PLEHN.
